UNITED STATES PATENT OFFICE.

WILLIAM L. GUMPRECHT, OF HARTFORD, CONNECTICUT, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,302,032.

Specification of Letters Patent. Patented Apr. 29, 1919.

Application filed April 5, 1916. Serial No. 89,015.

To all whom it may concern:

Be it known that I, WILLIAM L. GUMPRECHT, a subject of the King of Great Britain, residing in Hartford, in the county of

5 Hartford and State of Connecticut, have invented certain new and useful Improvements in Combined Type-Writing and Computing Machines, of which the following is a specification.

10 This invention relates to combined type-writing and computing machines, and more particularly to means whereby the pointing off or spacing between figures, as between dollars and cents, and between hundreds and 15 thousands, etc., is done automatically in the regular course of writing numbers. This invention is herein disclosed in the nature of an improvement on the application of

Frederick A. Hart, Serial No. 79,969, filed 20 February 23, 1916, (now Patent No. 1,282,823, dated October 29, 1918,) and also on the application of Andrew W. Steiger, Serial No. 87,672, filed March 30, 1916.

In the applications above referred to, the 25 mechanism includes an escapement wheel which coöperates with a fixed and a loose dog, both supported by a pivoted dog rocker, the latter controlled by character keys to effect letter-feed movements of the typewriter carriage. Said applications also include mechanism to effect double-space movements of the typewriter carriage at points where it is desired to space between the figures, by automatically shifting a stop 30 member which controls the throw of the loose dog; the stop member being shifted by means of a bail provided with tappets which are engaged by a projection on a tabulator stop, during the travel of the typewriter carriage.

In said application No. 87,672, there is shown means whereby, when the computing mechanism is disconnected by operating a disconnect key, the double-spacing mechanism is rendered ineffective.

A feature of the present invention is the provision of means whereby the double-spacing mechanism is rendered ineffective when a case-shift key is operated, as it is often 45 desirable to print in upper-case position without such double-spacing mechanism coming into use, particularly where the type-bars actuated by the numeral keys carry different types in the upper-case position.

A further feature of the present invention relates to means whereby a tappet plate, 55 designed for one class of work, as, for example, for writing numbers, as dollars and cents, where automatic spacing is desirable at the decimal position and between the hundreds and thousands denominations, etc., 60 may be readily replaced by another tappet plate carrying a differently arranged set of tappets suitable for a different class of work, as, for example, tabulating numbers 65 without decimals. For this purpose, the tappet plate may be removably attached to the swinging tappet bail as by means of screws, such arrangement being also convenient for the purpose of permitting the 70 tappets, which are subject to wear, to be case-hardened.

A further object of the invention is to provide a convenient and compact arrangement of the mechanism for shifting the tappets to inoperative position either by a case-shift key or the disconnect key of the computing mechanism.

The invention is shown as applied to a machine wherein a tappet on the carriage 80 operates a set of jacks *seriatim* when the computing zone is reached to move pin bars of the computing mechanism to position for the numeral keys to set up pins corresponding to the operated keys. Said tappet is 85 held in position to operate the jacks by a cam connected to a rock shaft, which shaft may be rocked to move the cam to inoperative position when the disconnect key for the computing mechanism is operated. In 90 the present invention, said rock shaft may also be actuated as by an arm on the platen-shift frame when a case shift key is operated. Said rock shaft, when actuated either by the disconnect key or the case-shift key, 95 swings to inoperative position the tappet-carrying bail which controls the double-spacing mechanism.

The present invention as herein shown, is applied to a combined typewriting and computing machine of the type shown in the patent to Hans Hanson, No. 816,319, dated 100 March 27, 1906, and in the patent of Frederick A. Hart, No. 1,190,171, dated July 4, 1916.

Other features and advantages will hereinafter appear.

In the accompanying drawings,

Figure 1 is a transverse vertical section of the machine, some of the parts being broken away, others being omitted.

Fig. 2 is a detail front elevation of the upper portion of the bracket in which the tabulator plunger stops are mounted, with part of the space-skipping means supported thereon.

Fig. 3 is a plan view of Fig. 2.

10 Fig. 4 is a skeleton perspective view illustrating my invention and showing the connection from the non-add key and the shift key to the tapped bail.

15 Fig. 5 is a fragmentary side elevation showing the tapped bail swung to its inoperative position and the computing machine set to disconnect.

20 Fig. 6 is a fragmentary front elevation of the typewriter escapement, showing the parts in a position to allow the typewriter carriage to move single letter-space distances.

25 Fig. 7 is a similar view with the escapement dogs rocked rearwardly in normal letter feeding.

Fig. 8 is a view similar to Fig. 7, except that the stop member is shifted to effect a double-space movement of the typewriter carriage.

30 Fig. 9 is a developed diagrammatic view, showing enough of the machine to illustrate the application of my invention in a simple manner.

The typewriting machine, except some of the carriage-feed devices which will herein-after be fully described, is of the usual Underwood construction, in which numeral keys 11 and alphabet keys 12 when depressed, move key levers 13 and 14 respectively to rock bell cranks 15 and swing type bars 16 upwardly and rearwardly about a fulcrum rod 17, causing types 18 and 19 to print against a cylindrical platen 20 on a shaft 21 which is rotatably mounted in a platen frame 22.

The platen is shiftable from lower to upper case position so as to allow either one of the types 18 or 19 to print, and is guided in its case-shifting movements by links 23 on a rock shaft 24. A shift key 25 when depressed, moves the lever 26 provided with an arm 27. The latter rocks a shift frame 28 on a rock shaft 29 to elevate a shift rail 30 carried thereby, moving the platen frame 22 upwardly and thus shifting the platen 20. Connection between the shift rail 30 and the platen frame 22 is made in the usual manner by a roller 31 on a finger 32 carried by a bar 33 on the platen frame.

60 The typewriter carriage is under constant tension of the spring drum 35 connected to the carriage by a strap 36 (Fig. 4). A rack 40 is pivotally mounted on the typewriter carriage 34 and engages with a pinion 41 to rotate an escapement wheel 42 provided

with teeth 43. The pinion 41 is connected with the escapement wheel by the usual one-way driving pawls 44. This escapement wheel coöperates with a loose dog 45 and a fixed dog 46 mounted on a dog rocker 47, 70 the dog rocker being pivotally supported by an escapement bracket 48.

The escapement, except the double-space feature herein described, is in many respects like that described in the patent to Rice ⁷⁵ et al., 769,804, dated September 13, 1904, and is operated in the following manner.

Each type bar 16 is provided with a heel 50 which, as the type bar swings to printing position, moves a universal bar 51 rearwardly against the tension of a spring 52 (Fig. 4) and rocks the dog carrier against the tension of a spring 53 (Fig. 6). The spring 53 serves the double function of swinging the loose dog about its pivot 54, 85 when the upper part of the dog rocker is moved rearwardly, and also returning the dog rocker to normal position. (See the aforesaid patent to Rice et al.) During the operation of the type bars 16, the dog rocker 90 47 is caused to vibrate transversely of the escapement wheel 42, thus bringing the teeth 43 of the escapement wheel into coöperation alternately with the loose and fixed dog. 95

When the dog rocker is moved rearwardly, the loose dog 45 is disengaged from a tooth 43 of the escapement wheel, after the fixed dog 46 has moved into a position to engage said tooth and hold the escapement wheel. 100 The loose dog, when thus disengaged, is permitted under the influence of the spring 53, to swing on its pivot until it is arrested by a stop 55 (Fig. 7), and when the dog rocker is brought back to normal position, 105 the loose dog will be brought into the path of the next succeeding tooth 43 of the escapement wheel 42, and the fixed dog will be withdrawn from the path of the teeth. The wheel being now free, is rotated, causing 110 said succeeding tooth 43 to swing the loose dog about its pivot 54 back to normal position (Fig. 4) against a stop 56 on the dog rocker 47, thereby arresting the carriage which has been moved a letter-space distance 115 by the spring drum 35.

The tabulator, except some of the stops on the stop bar, is of the regular Underwood construction, comprising keys 60, each of which, when depressed, swings a lever 61 about a fulcrum 62, to lift a denominational stop, in the form of a plunger 63, into the path of a column stop 64 on a stop bar 65, supported on the carriage 34. While the plunger is thus being moved, the typewriter carriage is released by the plunger engaging with a pivoted universal bar 66, to move a link 67 downwardly and swing a lever 68 about its pivot 69, thus raising the rack 40 out of engagement with the pinion 41, and 130

setting the typewriter carriage free from the escapement device, to be moved by the spring drum 35. The carriage will run until the tabulator stop 64 strikes the projected 5 plunger 63. Thus the carriage is arrested at the denominational position corresponding to the actuated key 60. In the present case I have shown eleven plungers, each being provided with a key 60 and a lever 61.

10 The computing mechanism comprises the usual denomination-selecting tappet 75 which, when a computing zone is reached during the travel of the typewriter carriage, rides upon a cam roller 76 located under a 15 set of jacks 77, where it is held in effective position by the usual spring 77a, as set forth in my Patent No. 1,237,895, dated August 21, 1917, so that the tappet rocks the jacks one at a time. Each jack moves a corre-

20 sponding thrust rod 78 downwardly to swing a lever 79 about a fulcrum 80, causing one of the links 81 to raise one of the computing bars 82 so that pins 83 thereon are brought into coöperative relation with 25 linkages 84. If a numeral key 11 is depressed while a computing bar 82 is raised, a stem 85 on the key lever 13 rocks a shaft 86 to move its corresponding linkage 84 and set one of the pins 83 on the computing bar

30 82. Thus the lower end of the pin 83 will be in a position when the computing bar is lowered, to be engaged by a horizontal bar 87 of the general operator which, at the proper time, is operated by the handle 88 to 35 move the bar 87 forward. The computing wheels 89 are operated and the computation completed substantially in the manner described in said Hanson Patent, No. 816,319.

To disconnect, or in other words, to make 40 the computing mechanism inoperative when writing numbers in the computing zone, the cam roller 76 is moved rearwardly where it will not engage with the tappet 75 during the travel of the typewriter carriage. This 45 is accomplished by actuating a non-add or disconnect key 90 which moves a thrust rod 91 to rock a lever 92 about its pivot 93. A roller 94 on the lever 92 engages with an arm 95 to rotate a rock shaft 96, and move 50 a frame 97, thus carrying the cam roller 76 out of the path of the tappet 75.

To disconnect during case-shifting operations, which is desirable when the numeral type bars are provided with another character, the cam roller 76 is moved to inoperative 55 position by providing the rock shaft 29 with an arm 98 having a roller 99 to engage with a cam in the form of a hook-shaped arm 100 secured to the rock shaft 96. It 60 will be seen that when the shift key 25 is depressed, the roller 99 moves downwardly on the cam 100, rocking the shaft 96 to move cam roller 76 out of the path of the tappet 75.

65 From the foregoing description it will be

seen that the cam roller is moved to inoperative position by an actuation of either a non-add key or a platen-shift key.

The shift key 25 and the non-add key 90 may be provided with a means for locking 70 them in their actuated position. In the present case I have shown the non-add key provided with the usual lock which comprises a pin 101 projecting laterally from the thrust rod 91 into a slot 102, the pin 101 75 being of a sufficient length to permit manipulation by the fingers for moving into a depressed portion 103 of the slot 102 when it is desired to lock the non-add key in its actuated position.

80 Double-space movements of the typewriter carriage at predetermined positions during its travel are effected in the following manner.

The stop 55 which normally controls the 85 swinging or loose dog 45, as hereinbefore described, is carried on a shiftable stop member or double-space permitting element 105 pivoted on a stud 106 secured to the escapement bracket 48, the lever being held in 90 position lengthwise of the stud by nuts 107 and 108 (Fig. 4). A second stop 109 on said member 105 is so positioned that when the member 105 is rocked from the Fig. 7 position to the position indicated in Fig. 8, 95 a stop 109 is brought into the path of the loose dog 45. It will be understood that in the Fig. 7 position, the swinging dog 45 is arrested by a pin 110 on the dog coming in contact with the stop 55, and in the Fig. 8 100 position, the loose dog is arrested by the rounded portion 111 engaging with the stop 109. If the dog rocker 47 is now rocked to disengage the fixed dog 46 from the escapement wheel, the latter is permitted a double-space movement as one tooth 43 has been 105 skipped by the pivoted loose dog 45.

The shiftable stop member or double-space permitting element 105 is held in its normal position by a spring 115 which 110 causes an arm 116 to bear against the escapement bracket 48, and is rocked to its double-space permitting position against the tension of said spring 115 in the following manner.

Those of the tabulator stops 64 which are 115 used for determining the position of a column of figures wherein it is desired to skip the punctuation spaces, are provided with extensions 117 which, during the travel of the carriage, engage with tappets 118 on a 120 plate 119 which is secured to a pivoted bail 120. The forward portion of the bail 120 is depressed whenever the extension 117 engages one of the tappets 118 which causes the stop member 105 which is connected to 125 said bail by a link 121, to be shifted to the Fig. 8 position, where the stop 55 has been taken out of, and the stop 109 brought into coöperative relation with the loose dog 45.

It is desirable to harden the tappets 118 130

as they are exposed to wear. I have therefore formed them on the plate 119 which may be secured to the bail 120 in any convenient manner, as for example, by means of screws 119^a. This arrangement permits the tappet plate 119 to be quickly removed and replaced by another plate with differently disposed tappets, positioned for automatic spacing at different denominational positions, as may be desired, for example, in writing numbers without monetary decimals.

To explain more clearly the double-space movements of the carriage, let it be assumed that the carriage has reached the ten thousands position in an adding zone. In this position the extension 117 of the tabulator stop 64 will be at the right of and adjacent to the middle tappet 118. If we now print in this position, the escapement mechanism will operate as usual to permit the carriage to advance a single letter-space distance. This movement of the carriage, however, will cause the tabulator stop to swing the bail 120 downward against the tension of the spring 115 and through the link 121 shift the stop 109 to the Fig. 8 position, so that on the next depression of a numeral key (the carriage now being in the thousands position) the loose dog (as the dog rocker swings rearwardly) will be permitted to move to the position shown in Fig. 8, where the dog 45 is arrested by the stop 109. When the dog rocker is allowed to return to normal position, the loose dog will move back of the adjacent tooth 43 and engage with the next tooth, permitting a double-space movement of the escapement wheel, and the carriage will be fed two letter-space distances.

Automatic double-spacing is in like manner effected at the decimal point position and at any other desired point in the computing zone, by correspondingly located tappets 118.

To make the double-spacing mechanism ineffective, which is desirable when the platen is shifted to upper case position, or when the computing machine is set to disconnect, I have found it advantageous to provide the rock shaft 96 with arms 125 having the pins 126 thereon which, (Fig. 9), normally restrain dwells 127^a of the cams 127, thus holding the levers 128 and bail 120 in position, but which, when the shaft is rocked, move in the cam slots 127 to swing forwardly the levers 128 pivoted to the tabulator plunger bracket 129 by screws 130. Thus the parts will be brought to the position shown in Fig. 5, where the bail 120 has been swung about its point of connection to the link 121 to lower the tappets 118 out of the path of the projection 117 on the tabulator stop 64.

It should be understood that the bail 120 can be swung about two pivots, and that means are provided to swing it about one

pivot to shift the double-space permitting element, and to swing it about the other pivot to render the double-space effecting means inoperative.

As hereinbefore described, the shaft 96 is rocked by means of the non-add key 90 or the case shift key 25. Therefore it should be understood that the double-space effecting mechanism is made ineffective by the actuation of either the non-add key or the case shift key.

To permit an adjustment of the bail 120 so that the tappets 118 coöperate with the tabulator stop at the proper time during the travel of the typewriter carriage, I have provided a screw 132 (Fig. 3), secured to one of the levers 128, and nuts 133 and 134, the nut 134 being provided with a shoulder 135 on which one arm of the bail 120 is pivoted. The other arm of the bail is pivoted on a stud 136 secured to the other lever 128. It will be seen that after loosening the nut 133, the nut 134 can be moved to the right or left, for the purpose of adjusting the bail 120 and the tappets 118. After the tappets 118 have been properly adjusted, the nut 133 is brought up tight against the shoulder 135 of the nut 134, thus locking both nuts on the screw 132. There is enough play between the two nuts to allow a swinging movement of the bail 120. It will be seen that only one side of the bail is provided with adjusting screws, the other side being free to move lengthwise of the pivot pin 136 during an adjusting operation.

Variations may be resorted to within the scope of the invention, and portions of the improvements may be used without others.

Having thus described my invention, I claim:

1. In a combined typewriting and computing machine, the combination of a carriage, a variable feed escapement for said carriage, an element traveling with said carriage, means controlled from said element for permitting double-space movement of the carriage at predetermined positions in its travel, printing mechanism, a case shift key, computing mechanism, a disconnect key for rendering said computing mechanism inoperative, and means controlled from either the case shift key or the disconnect key for rendering said double-space permitting means ineffective.

2. In a combined typewriting and computing machine, the combination with a paper carriage, of numeral keys, numeral types actuated thereby to print, computing wheels, means actuated by the numeral keys for controlling computations on said wheels, means to run up on said wheels numbers corresponding to the keys actuated, escapement mechanism to control the letter-feed movements of the carriage, means to automatically effect a double letter-space movement

of the carriage when the latter reaches a pre-determined denomination during the writing of a number, a key operable to disconnect the computing mechanism, a case-shift key, 5 and means operable by either of said last-mentioned keys to disconnect said double-space means.

3. In a combined typewriting and computing machine, the combination with a carriage and propelling means therefor, of escapement mechanism, computing devices, character keys, including numeral keys adapted to effect computations in said devices, type-bars actuated thereby and comprising upper and lower case type, case-shifting mechanism comprising a shift key, means actuated by the character keys for operating the escapement mechanism, means controlling the escapement mechanism to 20 automatically effect variable spacing between the written characters, and means operated by the case-shift key to render said escapement controlling mechanism and said computing devices simultaneously ineffective.

25 4. In a combined typewriting and computing machine, the combination with a carriage and propelling means therefor, of numeral keys, types operated thereby for printing members and other characters, computing mechanism controlled by said keys, escapement mechanism actuated by said keys, means operable automatically to control the escapement mechanism and to effect an unequal spacing between the several digits of a 30 number being written, a non-add key, means operated thereby to render ineffective said computing mechanism, a case-shift key, and means controlled by each of the two last-mentioned keys to render ineffective said escapement controlling means.

35 5. In a combined typewriting and computing machine, the combination with a paper carriage and propelling means therefor, of escapement mechanism, computing mechanism, a series of jacks mounted on the machine frame, a tappet on the carriage to operate said jacks *seriatim* during the travel of the carriage while the latter is in a computing zone, said jacks operable to control 45 the computing mechanism, a tappet holding device to hold said tappet in operative position, a rock shaft to which said holding device is connected for swinging the latter into and out of operative position, double-spacing 50 mechanism coöperating with the escapement mechanism to automatically effect a double-space movement of the carriage when a pre-determined denominational position is reached during the printing of a number,

55 60 said double-spacing mechanism comprising a swinging frame supported on the machine frame, means on the carriage to actuate said swinging frame, means forming a connection between said swinging frame and said rock shaft for swinging said frame into position

to make the double-spacing mechanism ineffective when the rock shaft is moved to position to make the computing mechanism ineffective, a case-shift key, and means actuated thereby to rock said shaft and thereby make ineffective the computing mechanism and said double-spacing mechanism.

6. In a combined typewriting and computing machine, the combination with a paper carriage and propelling means therefor, of escapement mechanism, computing mechanism, a series of jacks mounted on the machine frame, a tappet on the carriage to operate said jacks *seriatim* during the travel of the carriage while the latter is in a computing zone, said jacks operable to control the computing mechanism, a tappet holding device to hold said tappet in operative position, a rock shaft to which said holding device is connected for swinging the latter into and out of operative position, double-spacing mechanism coöperating with the escapement mechanism to automatically effect a double-space movement of the carriage when a predetermined denominational position is reached during the printing of a number, said double-spacing mechanism comprising a swinging frame supported on the machine frame, means on the carriage to actuate said swinging frame, means forming a connection between said swinging frame and said rock shaft for swinging said frame into position to make the double-spacing mechanism ineffective when the rock shaft is moved to position to make the computing mechanism ineffective, a non-add key, means actuated thereby to rock said shaft and thereby make the computing mechanism and said double-spacing mechanism ineffective, a platen on the carriage, a platen-shift frame, a case-shift key to actuate said shift frame and move the platen to upper-case position, and means operated by said shift frame to rock said shaft and thereby make the computing mechanism and said double-spacing mechanism ineffective.

65 7. In a combined typewriting and computing machine, the combination with a paper carriage and propelling means therefor, of escapement mechanism, computing mechanism, a series of jacks mounted on the machine frame, a tappet on the carriage to operate said jacks *seriatim* during the travel of the carriage while the latter is in a computing zone, said jacks operable to control the computing mechanism, a tappet holding device to hold said tappet in operative position, a rock shaft to which said holding device is connected for swinging the latter into and out of operative position, double-spacing mechanism coöperating with the escapement mechanism to automatically effect a double-space movement of the carriage when a predetermined denominational position is reached during the printing of a number,

- 5 said double-spacing mechanism comprising a swinging frame supported on the machine frame, means on the carriage to actuate said swinging frame, means forming a connection between said swinging frame and said rock shaft for swinging said frame into position to make the double-spacing mechanism ineffective when the rock shaft is moved to position to make the computing mechanism ineffective, a case-shift key, a disconnect key for the computing mechanism, and means operated by each of said keys to rock said shaft for making the computing mechanism and the double-spacing mechanism 10 ineffective.
- 15 8. In a combined typewriting and computing machine, the combination with a carriage and propelling means therefor, of numeral keys, numeral types operated thereby, computing mechanism controlled by said keys, escapement mechanism actuated by said keys and operable to effect a movement of the carriage at each operation of a key, means operable automatically to control the escapement mechanism and to effect an unequal spacing between the several digits of a number being written, a denomination selector for said computing mechanism, a support for said selector adapted to be moved to ineffective position, a lever connected to said automatically controlling means, a cam on said lever, and an arm connected to said support and adapted to operate said lever by said cam.
- 20 30 35 9. In a combined typewriting and computing machine, the combination with a carriage and propelling means therefor, of numeral keys, numeral types operated thereby, computing mechanism controlled by said keys, escapement mechanism actuated by said keys and operable to effect a movement of the carriage at each operation of a key, means operable automatically to control the escapement mechanism and to effect an unequal spacing between the several digits of a number being written, a denomination selector for said computing mechanism, a support for said selector adapted to be moved to ineffective position, a lever connected to said automatically controlling means, a cam on said lever, and an arm connected to said support and adapted to operate said lever by said cam.
- 40 45 50 55 60 65 10. In a combined typewriting and computing machine, the combination with a carriage and propelling means therefor, of numeral keys, numeral types operated thereby, computing mechanism controlled by said keys, escapement mechanism actuated by said keys and operable to effect a movement of the carriage at each operation of a key, means operable automatically to control the escapement mechanism and to effect an unequal spacing between the several digits of a number being written, a denomination selector for said computing mechanism, a support for said selector adapted to be moved to ineffective position, a lever connected to said automatically controlling means, a cam on said lever, a non-add key adapted to make said support ineffective, and an arm connected to said support and adapted to operate said lever by said cam.
- 70 75 80 85 90 95 100 105 110 115 120 125 130

a number being written, a denomination selector for said computing mechanism, a support for said selector adapted to be moved to ineffective position, a lever connected to said automatically controlling means, a cam on said lever, a case-shift key adapted to make said support ineffective, and an arm connected to said support and adapted to operate said lever by said cam.

11. In a combined typewriting and computing machine, the combination with a carriage and propelling means therefor, of numeral keys, numeral types operated thereby, computing mechanism controlled by said keys, escapement mechanism actuated by said keys and operable to effect a movement of the carriage at each operation of a key, means operable automatically to control the escapement mechanism and to effect an unequal spacing between the several digits of a number being written, a denomination selector for said computing mechanism, a support for said selector, a shaft carrying said support, an arm fast to said shaft, a lever connected to said automatically controlling means comprising a cam operated by said arm, a second arm on said shaft, a non-add key, and a lever operated by said non-add key adapted to be effective on said second arm to make said support ineffective, and thereby carry the automatically controlling means to ineffective position.

12. In a combined typewriting and computing machine, the combination with a carriage and propelling means therefor, of numeral keys, numeral types operated thereby, computing mechanism controlled by said keys, escapement mechanism actuated by said keys and operable to effect a movement of the carriage at each operation of a key, means operable automatically to control the escapement mechanism and to effect an unequal spacing between the several digits of a number being written, a denomination selector for said computing mechanism, a support for said selector, a shaft carrying said support, an arm fast to said shaft, a lever connected to said automatically controlling means comprising a cam operated by said arm, a non-add key adapted to carry the automatically controlling means to ineffective position, a case-shift device, and a lever operated by said case-shift device adapted to carry the automatically controlling means to ineffective position.

13. In a combined typewriting and computing machine, the combination with a carriage and propelling means therefor, of numeral keys, numeral types operated thereby, computing mechanism controlled by said keys, escapement mechanism actuated by said keys and operable to effect an escapement movement of the carriage at each operation of a key, means operable automatically to

- control the escapement mechanism and to effect an unequal spacing between the several digits of a number being written, a lever for supporting said automatically controlling means, a cam for said lever comprising a dwell, a follower adapted to engage said cam dwell to hold the automatically controlling means effective and adapted to be moved to cause the cam to shift the lever 5
- 10 to make said means ineffective, and means for simultaneously making said computing mechanism ineffective and operating said follower.
14. In a combined typewriting and computing machine, the combination with a carriage and propelling means therefor, of numeral keys, numeral types operated thereby, computing mechanism controlled by said keys, escapement mechanism actuated by said 45 keys and operable to effect a movement of the carriage at each operation of a key, means operable automatically to control the escapement mechanism and to effect an unequal spacing between the several digits of a number being written, a denomination selector for said computing mechanism, a support for said selector, a shaft on which said selector is mounted, an arm on said shaft, a non-add key adapted to be effective on said 50 arm, a second arm on said shaft, a case-shift device adapted to be effective on said second arm, a third arm on said shaft, a follower on said third arm, a lever connected to said automatically controlling means, a cam on 55 said lever coöperating with said follower, and a dwell on said cam to hold said automatically controlling means effective.
16. In a combined typewriting and computing machine, the combination with a carriage and computing devices, of an escapement for said carriage adapted normally to feed single letter-spaces, numeral keys for operating said escapement and computing devices, a stop adapted to cause said escapement to feed said carriage double letter-spaces, a bail adapted to operate said stop, tappets on said bail, a lug on said carriage adapted to operate said bail by said tappets, a swinging lever device on which said bail 60 is pivoted to enable it to be swung to and from said lug, a cam on said lever comprising a dwell, a follower for operating said cam normally resting in said dwell, and a key adapted to make said numeral keys ineffective to compute and adapted to move said follower and said cam to swing said bail to ineffective position. 65
15. In a combined typewriting and computing machine, the combination with a carriage and propelling means therefor, of numeral keys, numeral types operated thereby, computing mechanism controlled by said 70 keys and operable to effect a movement of the carriage at each operation of a key, means operable automatically to control the escapement mechanism and to effect an unequal spacing between the several digits of a number being written, a denomination selector for said computing mechanism, a support for said selector, a shaft on which said selector is mounted, an arm on said shaft, a non-add key adapted to be effective on said arm, a second arm on said shaft, a case-shift device adapted to be effective on said second arm, a third arm on said shaft, a follower on said third arm, a lever connected to said automatically controlling means, a cam on 75 said lever coöperating with said follower, and a dwell on said cam to hold said automatically controlling means effective.
16. In a combined typewriting and computing machine, the combination with a carriage and computing devices, of an escapement for said carriage adapted normally to feed single letter-spaces, numeral keys for operating said escapement and computing devices, a stop adapted to cause said escapement to feed said carriage double letter-spaces, a bail adapted to operate said stop, tappets on said bail, a lug on said carriage adapted to operate said bail by said tappets, a swinging lever device on which said bail is pivoted to enable it to be swung to and from said lug, a cam on said lever comprising a dwell, a follower for operating said cam normally resting in said dwell, and a key adapted to make said numeral keys ineffective to compute and adapted to move said follower and said cam to swing said bail to ineffective position. 80
15. In a combined typewriting and computing machine, the combination with a carriage and propelling means therefor, of numeral keys, numeral types operated thereby, computing mechanism controlled by said 85 keys and operable to effect a movement of the carriage at each operation of a key, means operable automatically to control the escapement mechanism and to effect an unequal spacing between the several digits of a number being written, a denomination selector for said computing mechanism, a support for said selector, a shaft on which said selector is mounted, an arm on said shaft, a non-add key adapted to be effective on said arm, a second arm on said shaft, a case-shift device adapted to be effective on said second arm, a third arm on said shaft, a follower on said third arm, a lever connected to said automatically controlling means, a cam on 90 said lever coöperating with said follower, and a dwell on said cam to hold said automatically controlling means effective.
